RECORD CHANGER PRESSURE ARM OR SIMILAR ARTICLE

Ernest O. P. Tatter, Addison, William A. Wagner, Park Ridge, and James G. Aurand, Chicago, Ill., assignors to Warwick Electronics Inc., Chicago, Ill., a corporation of Delaware

Filed Nov. 18, 1964, Ser. No. 82,672

Term of patent 14 years

(Cl. D26—14)

FIGURE 1 is a front, top and right side perspective view of a record changer pressure arm or similar article, showing our new design;

FIGURE 2 is a top plan view, to an enlarged scale;

FIGURE 3 is an inverted left side elevational view to the scale of FIGURE 2; and

FIGURE 4 is a rear elevational view thereof to the scale of FIGURES 2 and 3.

We claim:

The ornamental design for a record changer pressure arm or similar article, as shown.
